UNITED STATES PATENT OFFICE.

FRANK SOBEL, OF BROOKLYN, NEW YORK, ASSIGNOR TO METAL ARTCRAFT FIXTURE CO., OF NEW YORK, N. Y., A CORPORATION OF NEW YORK.

DESIGN FOR A DISPLAY STAND.

Application filed September 1, 1928. Serial No. 28,029. Term of patent 7 years.

To all whom it may concern:

Be it known that I, FRANK SOBEL, a citizen of the United States, residing at Brooklyn, in the county of Kings and State of New York, have invented a new, original, and ornamental Design for Display Stands, of which the following is a specification, reference being had to the accompanying drawing, forming part thereof.

In the drawing—

I claim:

The ornamental design for a display stand, as shown.

FRANK SOBEL.
